UNITED STATES PATENT OFFICE.

CHARLES W. TANN, OF DETROIT, MICHIGAN.

DESIGN FOR A MEDAL.

51,940.

Specification for Design.

Patented Apr. 2, 1918.

Application filed February 14, 1918. Serial No. 217,242. Term of patent 3½ years.

To all whom it may concern:

Be it known that I, CHARLES W. TANN, a citizen of the United States, residing at Detroit, in the county of Wayne, State of Michigan, have invented a new, original, and ornamental Design for Medals, of which the following is a specification, reference being had to the accompanying drawing, forming part thereof.

In the drawing, Figure 1 is a plan of one side of a medal, and Fig. 2 is a plan of the other side of a medal, showing my new design.

I claim:

The ornamental design for a medal as shown.

CHARLES W. TANN.
